CLAIM

The ornamental design for a bow making apparatus, as shown and described.

DESCRIPTION

FIG. 1 is a perspective view of a bow making apparatus showing my new design;
 FIG. 2 is a top plan view thereof;
 FIG. 3 is a bottom view thereof;
 FIG. 4 is a front elevation view thereof, the rear elevation view being a mirror image thereof;
 FIG. 5 is a right side elevation view thereof, the left side elevation view being a mirror image thereof;
 FIG. 6 is a top plan view of a bow making apparatus showing an alternate embodiment of my new design;
 FIG. 7 is a bottom view of a bow making apparatus showing the alternate embodiment of my new design;
 FIG. 8 is a front elevation view of a bow making apparatus showing the alternate embodiment of my new design, the rear elevation view being a mirror image thereof; and,
 FIG. 9 is a right side elevation view of a bow making apparatus showing the alternate embodiment of my new design, the left side elevation view being a mirror image thereof.
